INVENTOR

UNITED STATES PATENT OFFICE.

LEWIS D. FOWLER, OF OKLAHOMA, OKLAHOMA.

NAIL.

1,099,172.

Specification of Letters Patent.

Patented June 9, 1914.

Application filed December 12, 1912. Serial No. 736,249.

To all whom it may concern:

Be it known that I, LEWIS D. FOWLER, a citizen of the United States, residing at Oklahoma city, in the county of Oklahoma and State of Oklahoma, have invented a new and useful Nail, of which the following is a specification, reference being had to the accompanying drawings.

As nails and staples are now shaped, neither one will answer the purpose of the other. Moreover, a staple cannot be pulled out of a post or other object into which it is driven except by the aid of the wire or other member which is held or straddled by said staple.

An object, therefore, of the invention is to provide a nail or like article which will answer the purpose of both a nail and staple.

Other objects and advantages of the invention will be set forth in the ensuing description.

Referring to the drawings:—Figure 1 is a side elevation view of the improved nail. Fig. 2 is a perspective view. Fig. 3 is a fragmental perspective view of a wooden box, with the improved nail in use holding wire thereof. Fig. 4 is a perspective view showing the nail in use for securing wire to a fence. Fig. 5 is a sectional view showing two pieces of wood secured together by the nail, and showing how it clenches.

Referring to the several figures, in all of which like characters of reference designate like parts, the improved nail comprises a head 6 with two tangs or legs 7 and 8 depending integrally from it. While these tangs may be of the same or different size or shape in cross-section or be pointed in any suitable manner, one of them is made very much shorter than the other, the tang 8 in this instance being only about two-fifths the length of the tang 7, and being, in effect, a small spur depending from said head 6.

As is usual in the form of a nail, the head

6 is wider than its tangs 7 and 8, so that it can be caught by the claws of a hammer or other tool for pulling it, and in the present arrangement said head is made long enough to overhang both tangs.

In building wire fence, the longer tang 7 of the nail may be started into the post 9 by a person having charge of the spacing of the wires 10, the wires then being strung and placed on said nails as shown in the lower portion of Fig. 5, after which the latter is driven to place with its tangs astride said wires.

As arranged, the improved nail is more adapted for clenching than other nails, the point 11 of the longer tang 7 turning back toward and in line with the point 12 of the shorter tang 8 as shown in Fig. 5. With the nail clenched in this way, it forms a substantially C-shaped holding element whose line of pull or tension is at right angles to the plane of the parts 13 and 14 through which it passes; whereas, the clenching of the common nail forms a J-shaped holding element whose line of pull can rarely be brought to the right angle.

Having thus described the invention;— I claim:—

As a new article of manufacture, the herein described finishing nail including a flat head and two independent and spaced prongs projecting from the lower side of the head and having a parallel relation to each other, the edges of the flat head overhanging both of the prongs on all sides and one of the prongs being longer than the other prong, both of the prongs being pointed and the extremity of the longer prong being adapted to be turned back to clench the nail in position.

Witness my hand this 9 day of December, 1912.

LEWIS D. FOWLER.
